UNITED STATES PATENT OFFICE.

CHARLES A. JOHNSON, OF BODEGA, CALIFORNIA.

DESIGN FOR A SHOE SOLE.

Application filed July 6, 1925. Serial No. 14,003. Term of patent 14 years.

To all whom it may concern:

Be it known that I, CHARLES A. JOHNSON, a citizen of the United States, residing at Bodega, county of Sonoma, and State of California, have invented a new, original, and ornamental Design for a Shoe Sole, of which the following is a specification, reference being had to the accompanying drawing, forming part thereof.

The figure on the drawing is a perspective view of a shoe sole, showing my new design.

I claim:—

The ornamental design for a shoe sole, as shown.

CHARLES A. JOHNSON.
